UNITED STATES PATENT OFFICE

1,997,589

MATERIAL HANDLING MECHANISM

Nils D. Levin, Columbus, Ohio, assignor to The Jeffrey Manufacturing Company, Columbus, Ohio, a corporation of Ohio

Application April 30, 1930, Serial No. 448,626
Renewed January 9, 1935

4 Claims. (Cl. 198—8)

The present invention relates to a loading machine, and particularly to a machine of this class adapted to be moved about a mine over the mine tracks and positioned thereon to load out material from the various workings.

The general characteristics of the machine according to the present invention are: a truck-mounted discharge conveyor having a receiving end adapted to be positioned in proximity to the mine track and a delivery end adapted to deliver at elevated points to the rear of the truck, the conveyor being swingable relative to the truck about both vertical and horizontal axes; a gathering conveyor having its delivery end pivoted to and above the receiving end of the discharge conveyor for swinging movement in vertical and horizontal planes relative to the latter and for tilting movement about its own longitudinal axis; a pony truck adapted to be positioned beneath and placed in temporary connection with the gathering conveyor when the machine is to be transported from place to place in the mine; a jib mounted on the receiving end of the discharge conveyor and extending above the gathering conveyor; hoisting tackle connecting the jib and the gathering conveyor; and power devices for operating the conveyors, for operating the hoisting devices, for swinging the gathering conveyor in horizontal planes relative to the discharge conveyor to engage it in material to be loaded out, and for propelling the conveyor supporting means over the mine tracks. This general organization is fully described and claimed in my copending application Serial No. 480,216, filed September 6, 1930. The present application is concerned with such a conveyor combination wherein means are provided for maintaining the gathering conveyor at an angle to the discharge conveyor for gathering material alongside the path of movement of the machine.

Without further discussion of the general features of the invention, I shall proceed to describe it with reference to the illustrative embodiment shown in the accompanying drawings, in which:

Figure 1 is a side elevation of the rear end of the machine, or discharge conveyor section.

Figure 2 is a side elevation of the front end of the machine, or the gathering conveyor section.

Figure 3 is a section on line 3—3 of Figure 1.

Figure 4 is a section on line 6—6 of Figure 1.

Figure 5 is an enlarged view of certain clutch and brake mechanism appearing in Figure 1.

Figure 6 is a section on line 6—6 of Figure 2.

Figures 7 and 8 are plan views of the machine in two operating positions.

Figure 9 is a plan view of the machine arranged for long wall work.

Figure 10 is a detail, and

Figure 11 is another view of the machine arranged for long wall work.

As has been mentioned, the present machine comprises generally a discharge conveyor, and a gathering conveyor which have been indicated on the drawings as A and B, respectively. The discharge conveyor A is the same (with some additions, as will hereinafter appear) as the pit car loader described and claimed in my copending application, Serial No. 386,647, filed August 17th, 1929, in the United States Patent Office. Only a brief description of this conveyor unit will thus be necessary.

Referring particularly to Figures 1, 3 and 4, a truck frame 20 is provided with wheels as at 21 and 22 adapted to engage a mine track of which one of the rails is shown at 23. Mounted on frame or turntable 20 is a frame 24 for pivotal movement about a vertical pivot defined by ring 25, Figure 3. A shaft 26 is journaled in bearings 27 of frame 24, and pivotal about this shaft is a conveyor trough 21. The delivery end 27' of the conveyor trough is pivoted to the forward end about a shaft 28, and rests on a bolster 29 which is vertically adjustable on threaded rods 30 depending from the ends of brackets 31 fixed to the extremity of the forward portion of trough 27.

An electric motor 32 mounted on frame 24 drives a countershaft 33 through a sprocket chain 34. An idler sprocket 35 engages the chain to hold it clear of a winding drum 33 and its control appurtenances, Figures 3 and 4. A sprocket (not shown) on shaft 33 engages a sprocket chain 36, which is in driving connection with a sprocket 37 freely revoluble on shaft 26. Sprocket 37 may be placed in driving relation with shaft 26 by engaging clutch elements 38 and 39, Figure 3. Sprockets 40 and 41 fixed on shaft 26 engage the lower runs of conveyor chains 42 and 43 to drive the latter, these chains being connected by means of flights 44, which on the upper run of the chain pass over the bottom of trough 27 to propel material therewith.

A shaft 45 journaled in frame 24 beneath shaft 26 has keyed on its one end a sprocket 46 connected by means of a chain 47 with a sprocket 48 integral with the hub of sprocket 37. A sheave 49 freely revoluble on shaft 45 may be driven by the latter upon engagement of clutch elements 50

50 and 51, this sheave engaging a universally flexible chain 52 which is passed downwardly centrally of pivot ring 25 in engagement with sheaves 53 and 54 journaled beneath truck frame 5 20, and forwardly and rearwardly to engage sheaves 55 and 56 fixed to the axles of wheels 21 and 22.

10 Due to the described arrangement, the discharge conveyor is not only angularly adjustable as to its forward and rear sections about shaft 28, but it is also adjustable as a whole relative to the truck frame 20 about the horizontal axis defined by shaft 26 and the vertical axis defined by ring 25. Further, the conveyor may be driven 15 by the motor in any of its adjusted positions as may also the truck wheels, a self-contained unit being thus defined.

20 Referring particularly to Figures 3, 4 and 5, shaft 45 has a reduced end 45' to which is keyed one element 60 of a cone-clutch, this element being secured on the shaft by means of a cap screw 61 and washer 62. Loosely mounted on shaft 45 immediately adjacent element 60 is a drum 63 having formed integral with one side 25 wall thereof, a conical flange 64 for cooperation with element 60. The opposite wall of the drum has integral therewith a cylindrical flange or pulley 65 with which is adapted to cooperate a brake band 66.

30 The hub of the drum within flange 65 is provided with a peripheral shoulder 67 behind which is engaged an internal peripheral flange 68 of a two-part sleeve 69 slidable on the external surface of a bearing 69' for shaft 45. Sleeve 69 35 has diametrically opposite integral studs 70 and 71 engaged in longitudinal slots formed in arms 72 and 73 of a shipper member pivoted at one end on a pin 74 mounted in a bracket fixed to frame 24. A prolongation of arm 73 is pivoted through a longitudinally extending slot to a nut 75 which is engaged on a screw-threaded portion 76 of a shaft 77 journaled in frame 24 parallel to shaft 45. Shaft 77 at its ends is provided with cranks 78 and 79, respectively, so that the shaft may be 40 rotated from either side of the machine. It will be evident that rotation of shaft 77 will cause nut 75 to travel along threaded portion 76, thus oscillating the shipper member and causing axial displacement of sleeve 69 in one direction 45 or the other on shaft 45. Due to the connection between sleeve 69 and drum 63, the latter is forced to follow the movements of the former, so that by proper manipulation of the crank 78 or 79, clutch elements 60 and 64 may be engaged or 50 disengaged. Flange 65 is sufficiently wide so as never to pass out of fully cooperating relation with band 66.

55 Referring particularly to Fig. 5, a lever 80 is fixed at its lower end on a shaft 81 which extends 60 parallel to shaft 45 and is mounted between parallel walls of the bracket already mentioned as supporting the shipper, the outer of these walls being shown at 82. At its end opposite to that shown in Figure 5, shaft 81 is journaled in the 65 side wall of frame 24. One end of band 66 engages shaft 81, while the other end is secured to one end of a connecting member 83 whose other end is pivoted to a pin 84 carried by lever 80 parallel to shaft 81, but spaced from the latter longitudinally of the lever. It will be apparent that 70 oscillation of lever 80 will tension or loosen band 66 as desired. In order that the band may be held in a tensioned position a toothed-member 85 is fixed to the side of the frame in position to co- 75 operate with a dog-point 86 mounted on lever 80.

A cross brace 87 extends between lever 80 and a similar lever 88 fixed to shaft 81 on the other side of the machine so that the brake may be operated from either side of the machine. Levers 80 and 88 are of spring material, and thus yieldable to permit disengagement of elements 85 and 86.

5 10 Trough 27 at its forward end extends downward in proximity to the track rails, and has a forward portion 27" adapted to assume a substantially horizontal position immediately above the rails. At substantially the end of the downwardly extending portion of the trough 27, there is erected an upright frame generally denoted at 89, this frame being composed of structural 15 steel parts.

10 On a laterally projecting horizontal plate 120 secured to trough 27 forwardly of drum 63 and on the same side of the machine as the latter are mounted on vertical axes two sheaves 121 and 122, Figs. 1 and 8. On the other side of the trough directly opposite these sheaves is a sheave 123 mounted on a vertical axis on a plate 124 secured to the trough, Fig. 8.

15 In order that the forward end of the conveyor trough may be properly supported, I have provided a pair of brackets as at 129, Fig. 1, secured to the lower ends of transversely opposite uprights of frame 89, respectively, and supporting flanged rollers as at 131 on transverse horizontal 20 pins as at 132, Fig. 9. Rollers 130 and 131 are adapted to rest upon and engage the track rails when the machine is in loading positions.

25 At the forward end of trough section 27" and on the underside thereof is secured a vertical pivot 30 member 133, Fig. 2, which is engaged by one end of an arm 134 having an expanded vertical web portion 135 adapted to swing about the forward end of the trough. Just above the top of the trough web 135 has secured thereto a horizontal angle bar 136 on the lower side of the horizontal web of which is mounted a centrally disposed lug 137. To the end of the conveyor trough and at its top is secured a circular casting 138 having a peripheral upstanding rib 139 which forms a guide for lug 137. Casting 138 and rib 139 are adapted to support any weight imposed thereon through bar 136.

35 The gathering conveyor B, Figs. 2 and 6, comprises a bottom plate 140 bent upward at one 40 end so as to be adapted to project above the receiving end of the discharge conveyor A with its forward portion in substantially horizontal position. Extending longitudinally of plate 140 and secured thereto substantially centrally thereof 45 are upper and lower chain guides 141 and 142 spaced apart by means of blocks 143. Guides 141 and 142 are provided with opposed longitudinal grooves 144 and 145, in which are engaged elements of a chain 146 which is flexible in planes 50 both parallel and perpendicular to plate 140. At intervals, flights 147 are secured to chain 146 to project laterally of plate 140 so as to propel material therealong and on one side or the other of the chain guiding means depending upon the direction of travel of the chain. A plate 148 is secured to the tops of the upper chain guide members 141, and extending longitudinally and centrally of plate 148 is an upright baffle plate 149. At its forward end plate 149 terminates at an 55 upright post 150 having an upper bifurcated end, Fig. 2. At its rearward end the plate terminates in a block 151 in which are mounted on a horizontal transverse axis a pair of sheaves 152.

60 In a casting 153 at the rear end of the gathering 60

conveyor and mounted upon the chain guides is journaled a shaft 154 in perpendicular relation to base plate 140. On the lower end of shaft 154 is fixed a sprocket 155 which engages chain 146 5 to drive the latter. To the upper end of shaft 154 is keyed a bevel gear 156 engaged by a bevel pinion 157 keyed to the end of a shaft 158 journaled in a bearing 159. A reversible motor 160 is mounted on the tops of the chain guides with its armature shaft in alignment with shaft 158 and in driving connection therewith through a coupling 161.

The inclined portion of conveyor B is provided with upwardly extending side plates 162 and 163 15 to hold the coal on plate 140 as it travels up the incline, the rearward end of plate 140 being cut away, as indicated at 164, to permit the coal to drop readily into the receiving end of the discharge conveyor trough. Due to its disposition, 20 gear 156 is adapted to engage and assist in propelling the coal from the gathering to the discharge conveyor.

A casting 164 secured to the underside of plate 140 at its rearward end has integral therewith a 25 pair of trunnions of which one is shown at 165, Fig. 4, these resting on the angle member 136 and being engaged by retaining angles as at 166. It will be noted that the trunnions are so journaled as to give them a considerable freedom of movement in an upward direction relative to the mounting member constituted by elements 134, 30 135 and 136.

A boom 112 is pivoted on a vertical axis on the upper forward end of frame 89 and is adapted to 35 extend above the gathering conveyor. A rope 169 having one of its ends engageable with drum 63 may have its other end portion reeved about suitable pulleys and lead from the end of the boom 112 downward to pulleys 151 and 152 on the gathering conveyor. By suitable manipulation of the drum, the gathering conveyor may be elevated as for disposition on a pony truck for transportation. This arrangement is fully described in my above mentioned application, Serial No. 480,216. 40

45 Due to the pivoting of the boom and the gathering conveyor, the latter may be swung about its pivot 133 in elevated position, the placing of the last named pivot being such relative to the delivery end of the gathering conveyor, as to maintain the latter always in proper delivering position relative to the receiving end of the discharge conveyor.

According to Figs. 7 and 8, the discharge conveyor A is disposed on a straight track section and supported by means of its truck mounting, and 50 also by means of rollers 130 and 131. The gathering conveyor B rests on the mine floor in advance of the track, and is being dumped into a mass of material through a rope 184 secured at its forward end to a roof-jack 185 and its rearward end engaged with drum 63 for winding thereon. The intermediate portion of the rope is guided clear of the machine by sheave 122. When the horizontal portion of conveyor B has been dumped into the material, a jack 186 is placed to the left 55 of the machine, rope 184 is reeved around sheaves 121 and 123 as shown in Fig. 13, around a pulley 187 having its block 188 anchored to jack 186, and its forward end caught in the upper slotted end of post 150, an eye 189 fixed to the end of the 60 rope preventing the latter from pulling away from the post. Upon exerting tension on the rope through manipulation of the winding drum, conveyor B may be swung to the left to engage its gathering end laterally in the material. Upon the 65 completion of this operation, jack 186 may be

moved to the right of the machine and rope 184 70 trained around sheave 122 and pulley 187 to swing conveyor B to the right, the direction of rotation of motor 160 being reversed.

Rope 184 being secured to conveyor B at the 75 top of post 150 has a tendency to tilt the conveyor about its longitudinal axis, this tendency being accommodated readily by the bearings for trunnions 165. This tilting of the gathering conveyor gives it a superior scraping action, and allows 10 it to engage itself readily under the material and leave a clean floor. It is, of course, understood that the operations described in connection with Figs. 12 and 13 are merely suggestive, and that the machine may be operated in various other 15 ways.

Under some conditions of long wall work, it is 20 desirable that means be provided for rigidly maintaining conveyor section B in rectangular relation to discharge section A. Under these 25 conditions, baffle 149 is interrupted so that a yoke 190 may be fixed on plate 148, Figs. 9 and 10, the yoke being provided at its top with an aperture 191. Plate 124 is extended as at 124' and provided with an aperture in which is adapted to 30 be inserted the bent end of a bar 192 whose other similarly bent end may be inserted in aperture 191. The extremities of bar 192 are provided with collars 193 and 194 retained in position by means of cotter pins. A post 195 is mounted on 35 the gathering conveyor intermediate yoke 190 and the pivoting axis of the conveyor, and the end of cable 169 is adapted to be caught in the eye of this post, an intermediate portion of the cable being reeved in a block 196 hung on a jack 40 45 197 to the opposite side of the track from the gathering conveyor. Upon winding the cable on drum 63, the machine is advanced along the track to engage the gathering conveyor in material to the side thereof. Bar 192 has its ends 40 loosely engaged in the apertures above mentioned, so that the tilting of the gathering conveyor is not interfered with.

When block 196 can be conveniently positioned on the same side of the track as the gathering 45 conveyor, the cable extremity may be caught in the eye of post 150, and the drum end of the cable reeved about sheaves 121 and 123, as shown in Fig. 11. Under these conditions, the grace bar 50 55 192 is unnecessary, since the rectangular relation of the conveyors is naturally retained.

It will be understood that while I have described a specific embodiment of my invention, I do not limit myself except as determined in 55 the following claims:

I claim:

1. In a machine of the class described, a movable frame, an elongated conveyor having a pivotal connection at one end with said frame 60 whereby the conveyor is horizontally swingable relative to the frame to engage the conveyor laterally in material to be gathered and freely tilt- 65 able through a limited range about its longitudinal axis toward the material, means for locking the conveyor to the frame in angularly projecting relation to the line of movement of the latter with the conveyor tiltable about its longitudinal axis, and means for propelling the frame with the conveyor in such relation to engage the latter in the material to be gathered, said locking means serving to maintain the conveyor in its angular relation to the frame against the resistance of the material.

2. In a machine of the class described, a mov- 70 75

able frame, an elongated conveyor having a pivotal connection at one end with said frame whereby the conveyor is horizontally swingable relative to the frame to engage the conveyor laterally in material to be gathered and freely tilt-
able through a limited range about its longitudinal axis toward the material, the conveyor having a portion provided with an upwardly open aperture, a horizontally extending bar connected at one end to the frame and having at its other end a vertically extending portion loosely insertable in said aperture to maintain the conveyor in angularly projecting relation to the line of movement of said frame while permitting it to tilt about its longitudinal axis, and means for propelling the frame with the conveyor in such relation.

3. In a machine of the class described, a movable frame, an elongated conveyor having a pivotal connection at one end with said frame whereby the conveyor is horizontally swingable relative to the frame to engage the conveyor laterally in material to be gathered, and freely tilt-
able through a limited range about its longitudinal axis toward the material, readily disconnectible means for locking the conveyor to the frame in angularly projecting relation to the line of movement of the latter, a winding drum on the frame, means for rotating said drum, and a rope wind-
able on said drum and connected to said conveyor above the tilting axis of the latter with its intermediate portion trained around guide means external to the machine, the rope being tensioned upon rotation of the drum to swing said conveyor

relative to said frame, or, with said locking means effective, to advance said frame and conveyor to engage the latter in the material to be gathered, said locking means serving to maintain angular relation of the conveyor to the frame against the resistance of the material.

4. In a machine of the class described, a movable frame, an elongated conveyor having a pivotal connection at one end with said frame whereby the conveyor is horizontally swingable relative to the frame to engage the conveyor laterally in material to be gathered, and freely tilt-
able through a limited range about its longitudinal axis toward the material, readily disconnectible means for locking the conveyor to the frame in angularly projecting relation to the line of movement of the latter, a winding drum on the frame, means for rotating said drum, and a rope windable on said drum and connected to said conveyor above the tilting axis of the latter with its intermediate portion trained around guide means external to the machine, the rope being tensioned upon rotation of the drum to swing said conveyor relative to said frame, or, with said locking means effective, to advance said frame and conveyor to engage the latter in the material to be gathered, said locking means serving to maintain angular relation of the conveyor to the frame against the resistance of the material, the rope being guided from the drum on the side of the machine opposite the conveyor when the latter is in locked position, and being connected to the conveyor at a point removed from its pivot.

NILS D. LEVIN.
